UNITED STATES PATENT OFFICE.

JOHN V. CAVALERO, OF NEW YORK, N. Y.

NON-REFILLABLE BOTTLE.

1,186,968.

Specification of Letters Patent. Patented June 13, 1916.

Application filed May 12, 1914. Serial No. 833,021.

To all whom it may concern:

Be it known that I, JOHN V. CAVALERO, a citizen of the United States, residing in the city of New York, borough of Manhattan, county and State of New York, have invented a certain new and useful Non-Refillable Bottle, of which the following is a specification.

This invention is a liquid container, and the object in view is to prevent refilling the container with spurious liquor after it shall have been emptied of its original contents. The device enables the liquid to flow freely when the bottle is turned to a decanting position, for the reason that air can enter the container during the outflow of the liquid, the inflow of air and the outflow of liquid taking place simultaneously and without interference. Furthermore, the parts are so simple in construction and easy of assemblage that the article is manufactured rapidly, economically and without resorting to skilled labor.

The invention is embodied in a container the mouth portion of which is provided with an upstanding flange positioned intermediate an internal shoulder and an external shoulder, a hollow member clamped in a fixed position by contact with said internal shoulder and an exterior cap, said hollow member being provided with a liquid passage and with cavities at top and bottom, a cap attached to the container and operating to clamp the hollow member fixedly in position against the internal shoulder, a disk valve adapted to be seated against the internal shoulder, and a separate valve positioned in the upper cavity of the hollow member, said separate valve being provided with a stem adapted to contact with the disk valve.

Other features and advantages of the invention will appear from the following detailed description.

In the drawings, Figure 1 is a vertical section through a non-refillable bottle embodying my invention, and illustrating said bottle in a normal upright position. Fig. 2 is a vertical section similar to Fig. 1, with the bottle in a decanting position. Fig. 3 is a plan view of the disk valve.

The bottle A may be of any suitable shape and dimensions, but as shown the wall of the bottle is thickened adjacent to the mouth portion thereof, as at α , said bottle being provided with an upwardly projecting

flange b . This flange is positioned intermediate the inner and outer edges of the bottle at the mouth portion thereof, and shoulders b' b^2 are thus formed at the mouth portion of the bottle, the shoulder b^2 being exterior to the upstanding flange b , whereas the shoulder b' is positioned interiorly with respect to said flange.

B is a hollow member, the same consisting of a single piece of material. This hollow member is provided at its upper portion with a cavity c , the lower reduced part of which forms a valve seat at c' . Said member is provided with a longitudinal passage d , the upper part of which opens into the cavity c , whereas the lower end of said passage opens through the horizontal bottom face of the member. An exterior flange e is provided on member B at the lower part thereof, and depending from the under face of this member is a second flange f , the diameter of which is equal substantially to the interior diameter of the flange b at the mouth of the container. Said flange b of the container is provided, preferably, with an exterior screw thread g , and to this flange is screwed the lower female threaded part of a cap C, whereby the cap C is attached directly to a threaded part of the container A. If desired, the cap C may be attached in any other suitable way to the container, as for example by omitting the engaging screw threads and employing an exterior metallic band which covers the connection or joint between the container and the cap. It is preferred, however, to attach the cap to the container by the screw threads and to employ means for sealing said cap hermetically to the container; one way of sealing the parts together being to employ a cement of the character known as "glass cement" applied to the threads or to the contacting faces of the cap and the shoulder b^2 . When the cap is sealed to the container, it is apparent that said cap cannot be removed without breaking the container, thus effectually preventing the device from being refilled with spurious or other liquor after it shall have been emptied of its original liquid contents.

The cap C is shown as having a head h integral with the sleeve-like portion of said cap, and in one side wall of the cap is a liquid outlet h' , the latter being in the form of an aperture surrounded by a flange h^2 .

To provide for the ingress of air simultaneously with the outflow of liquid, it is desirable to employ an air inlet *i* preferably in that wall of the cap *C* opposite to the outlet *h'*, but if desired this air inlet *i* may be otherwise positioned, and it may be omitted entirely.

The external diameter of the hollow member *B* is less than the internal diameter of the sleeve portion of the cap, and thus an annular liquid passage *j* is provided between the opposing surfaces of the hollow member and the cap.

An important feature of my invention is the provision of means for clamping the hollow member *B* fixedly in position by the exterior cap *C*. To this end the head *h* of the cap is shown as having studs *k* adapted for contact with the upper edge of member *B*. These studs *k* are integral with the head and are spaced with respect to each other, said studs being positioned on the under face of the head and adapted for contact with the upper edge of the hollow member. If desired, the top edge of the member *B* may be, and preferably is, provided with a shallow annular channel *k'* into which the depending studs *k* are adapted to fit, so that the studs will travel within the groove in the operation of screwing cap *C* upon the threaded portion *g* of the container.

D is a disk valve which is positioned loosely within the space formed by the depending flange *f* of member *B*. This disk valve is adapted to rest upon or be seated against the internal shoulder *b'* at the mouth of the bottle. The disk valve is free to have a limited sidewise movement within a cavity *f'* provided at the bottom of member *B* by the depending flange *f*. Movement of the disk valve toward the under face of the hollow member is limited or arrested by studs *l* which are integral with the member and depend from the under face thereof, whereby the studs *l* so limit the movement of the disk valve *D* that a space is provided between the valve and the member for the outflow of the liquid and the inflow of air when the bottle is turned to a decanting position. Said disk valve is provided, also, with a series of fingers *D'*, any suitable number of which extend radially from the peripheral or edge portion of the disk valve. These fingers are in contact with the inner face of the depending flange *f* so as to retain the disk valve in proper position within the flange, to direct the movement of the disk valve in a way and to provide a permanent space between the edge of the disk valve and the inner face of flange *f*, thus providing the required space for the outflow of liquid and the inflow of air between the disk valve and the chamber or cavity within which it is positioned.

In addition to the disk valve *D*, my in-

vention embodies a separate valve *E*, the same being provided with a depending stem *E'* which fits loosely within the longitudinal passage *d* of the hollow member. Said valve *E* is positioned within the cavity *c* of said member so that the valve will occupy the seat *c'* when the bottle is in the normal upright position. The valve and its stem are free to have a limited movement within the cavity *c* and passage *d* of the hollow member, but this movement in one direction is arrested by the valve fitting the seat *c'*, whereas the movement in the opposite direction is arrested by a stop-pin *C'* integral with the head *h* of the cap and depending therefrom into a desired relation to the upper face of the valve. The stem *E'* of said valve terminates a suitable distance above disk valve *D*, and when the valve *E* occupies its seat within the member said stem *E'* is adapted to contact with the disk valve should the latter stick within the cavity *f'* by the adhesion of the valve *D* to the walls of the lower cavity.

The disk valve *D* is shown as having a port *D'*, said port being within the edge of the valve and consisting of an aperture of small dimensions. This port is for the purpose of providing a vent for the inflow or outflow of air, and while it may be desirable for certain reasons to employ the port in the disk valve, I would have it understood that my invention is not restricted to the use of said port.

The operation is as follows: With the container in the upright position shown in Fig. 1, valve *D* occupies the seat afforded by the shoulder *b'* of the container, and valve *E* rests upon the seat *c'* at the bottom of the chamber *c* within the hollow member. Now when the bottle is tilted to the decanting position, as in Fig. 2, the pressure of the liquid against valves *D* *E* will unseat said valves, the movement of valve *D* being arrested by the stop pins *l*, whereas the outward movement of valve *E* will be arrested by contact with the stop-pin *C'*. With the valves unseated, liquid is free to flow around the lower edge of valve *D* through the passage *d* and below the edge of valve *E*, the liquid flowing out of chamber *c* over the edge of hollow member *B* and through the annular passage *j* and out through the exit aperture *h'*. At the same time air is free to flow through inlet *i*, the upper part of passage *j*, over the top edges of member *B*, valve *E*, through the upper portion of passage *d*, and over the top edge of valve *D* and into the container, whereby liquid is free to flow out of the container and air will flow into the container simultaneously with the liquid outflow.

It is apparent that access cannot be obtained by a wire or other implement to the valves, or either of them, for the reason that

the wire must be inserted either at inlet *i* or outlet *h'* and thence pass through chamber *j* over the top of the hollow member *B* so as to obtain access to valve *E*.

5 It will be understood, accordingly, that it will be difficult to obtain access to valve *E* in order to hold the same in an open position, but as the wire cannot pass said valve *E*, it will be a physical impossibility to so 70
10 manipulate the wire as to reach the inner valve *D*. The construction described thus precludes the mechanical manipulation of the valves for refilling the bottle, and it is believed that it will not be possible to refill 75
15 the bottle by admitting liquid under pressure through the cap, for the reason that the pressure of liquid against valve *E* will have a tendency to seat said valve, the stem *E'* of said valve will tend to press valve *D* 80
20 to its seat, whereby the admission of liquid under pressure will force the valves to their respective seats.

It is apparent that the cap, the hollow member, the valves and the container may 85
25 be composed of any suitable material, such as glass, porcelain, or any other material suitable for the purpose.

I attach some importance to the use of a disk valve, which valve is composed of 90
30 light-weight material or composition, for the reason that after decanting the liquid a few drops of it will adhere either to the under face of the disk valve or to its seat so that when the disk again contacts with the 95
35 seat the drops of liquid will spread and the pressure of air against the top of the disk valve operates to bring about a condition to effect the sealing of said disk valve directly at the outlet from said container.

40 It is apparent, further, that the pins or studs on the closed head of the cap adapted for contact with the top edge of the hollow member may be reversed, *i. e.* said studs or pins may be provided on the top edge of the 100
45 hollow member for contact with said cap, whereby the hollow member is clamped in position between the container and the cap and spaces are provided to connect the upper chamber *c* of the hollow member with 105
50 the annular chamber *j* between said hollow member and the external cap.

Having thus fully described the invention, what I claim as new, and desire to secure by Letters Patent is:

55 1. In a device of the class described, the combination of a container, an external cap fixedly secured thereto, said cap having a side liquid outlet, a hollow member positioned within the cap and retained fixedly 110
60 in position by engagement with the cap at the top thereof and with the container at its base, the diameter of said hollow member being less than the internal diameter of 115
65 said cap to provide an intermediate air and liquid space around the hollow member to

connect with the outlet, and a plurality of operating valves retained in position by said hollow member.

2. In a device of the class described, the combination of a container, an external cap 70
75 fixedly secured to the container, said cap having a liquid outlet in one side thereof, a hollow member positioned within the cap and retained fixedly in position by contact with the cap and the container, the diameter of said hollow member being less than the internal diameter of the cap to form an intermediate space opening into said liquid outlet, and separate valves incased within the hollow member, one of said valves being seated on said member and the other valve seated on the container. 80

3. In a device of the class described, the combination of a container, an external cap 85
90 fixedly secured to the container, said cap having a liquid outlet in one side thereof, a hollow member positioned within the cap and retained fixedly in position by contact with the cap and the container, the diameter of said hollow member being less than the internal diameter of the cap to form an intermediate space, a disk valve positioned within the lower part of the hollow member and seated on the container, a second valve incased within the hollow member at the upper part thereof and seated thereon, and means on the cap and on the hollow member for limiting the movement of said valves relative to said hollow member. 95

4. In a device of the class described, the combination of a container, an external cap 100
105 fixedly secured to the container, said cap having a liquid outlet in one side thereof, a hollow member positioned within the cap and retained fixedly in position by contact with the cap and the container, the diameter of said hollow member being less than the internal diameter of the cap to form an intermediate space, a disk valve positioned within the lower part of the hollow member and seated on the container, and a second valve incased within the upper part of said hollow member and seated thereon, said second valve having a rounded lower face and provided with a stem extending through the 110
115 hollow member and adapted for contact with the disk valve.

5. In a device of the class described, the combination of a container, an external cap 120
125 fixedly secured to the container, said cap having a liquid outlet in one side thereof, a hollow member provided with a chamber and with a groove in the edge above the chamber, studs depending from the cap and fitted in the grooved edge of said hollow member, a valve positioned in the chamber and seated on the hollow member, and a stoppin extending from the cap and contacting with said valve.

6. In a device of the class described, the 130

combination of a container having an internal shoulder, an external cap secured to the container and provided with a liquid outlet, an interior member of less diameter than the cap provided with a chamber having a curved and recessed valve seat, said interior member being provided also with a depending flange adapted to contact with the internal shoulder of the container to form a lower cavity, a valve positioned in the lower cavity, a restricted passage connecting the upper chamber with the lower cavity, and a valve provided with a convex lower face to engage the curved valve seat and with a depending stem to be positioned within the passage and to extend into the lower cavity when the stem valve is in its closed position.

7. In a device of the class described, the combination of a container having a mouth, an external cap provided with a liquid outlet, an interior member retained immovably between the cap and the container and above

the mouth of the container, said interior member being provided with an upper chamber and with a passage leading from the chamber to the mouth of the container, a disk valve mounted for movement between said interior member and the mouth of the container, and a stem valve having an enlarged head mounted for rocking movement in the upper chamber and having its stem adapted to engage the disk valve when in its closed and the opened position of the disk valve, and a depending stop pin on the cap to limit the movement of the stem valve in one direction.

In testimony whereof I have signed my name to this specification in the presence of two subscribing witnesses.

JOHN V. CAVALERO.
